Fig. 5

Fig. 6

Fig. 7

FIG. 1 is a side elevational view of a lamp shade showing my new design.

FIG. 2 is a top plan view thereof.

FIGS. 3, 4, 5 and 6 are side elevational views of the shade, on the larger scale than FIG. 1, looking in the directions indicated by the arrows and numerals 3, 4, 5 and 6, respectively, on FIG. 2.

FIG. 7 is a vertical sectional view in the plane of the line 7—7 of FIG. 2.

Parts of the design are lined for color in the drawings.

The fragmentary standard and the ground line are shown in broken lines in FIG. 1 for illustrative purposes only.

I claim:

The ornamental design for a lamp shade, as shown and described.
